UNITED STATES PATENT OFFICE

2,166,805

CONTROL CIRCUIT

Robert B. Dome, Bridgeport, Conn., assignor to
General Electric Company, a corporation of
New York

Application April 28, 1936, Serial No. 76,789

6 Claims. (Cl. 250—20)

My invention relates to reactance control circuits and more particularly to such circuits as utilized in the control of frequency. Still more particularly my invention relates to signal seeking circuits employed in radio receivers, particularly of the superheterodyne type, and it has for one of its objects to effect certain improvements in the control of the local oscillator utilized in such circuits.

10 In signal seeking circuits employed in superheterodyne receivers means have been employed to control the frequency of the local oscillator in response to variations of the intermediate frequency of the receiver and in such a way as 15 to compensate for such variations. Thus this compensating means has the effect of maintaining the intermediate frequency constant notwithstanding that the tuning control is moved over a considerable range in proximity to a position where the receiver is tuned to a desired frequency. One means for effecting this control involves the use of an electron discharge device 20 having electrodes connected in shunt with the oscillatory circuit of the local oscillator and 25 varying the impedance between the electrodes in response to variations of the intermediate frequency to control the frequency of the local oscillator. This means presents certain difficulties due to misalignment between the local oscillator with the other tuned circuits of the receiver, this misalignment producing variations 30 in the intermediate frequency as the tuning control is varied from one end of its range to the other. One object of my invention is to provide 35 means for obviating these difficulties.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing in which the single figure represents an embodiment of my invention.

Referring to the drawing, I have conventionally indicated therein a radio receiver having an antenna 1, a tuned input circuit 2, which may include one or more radio frequency amplifiers, a first detector 3, an intermediate frequency amplifier 4, a frequency discriminating circuit 5, a second detector 6, and an output circuit 7. This receiver also comprises an electron discharge oscillation generator 8, the oscillations of which may be supplied through a switch 9 and

condenser 10 to the first detector 3 whereby they are caused to beat with the received oscillations to produce a desired intermediate frequency which in turn is supplied to the amplifier 4. The electron discharge oscillation generator 8 includes a frequency determining oscillatory circuit 11 comprising an inductance 12 connected effectively in shunt with a tuning condenser 13 through alignment condenser 15 and by-pass condenser 14. An additional condenser 16 is 10 connected in shunt with the variable condenser 13 and is adjustable for purposes of initial adjustment of the receiver.

The tuning condenser 13 of the oscillator is arranged for unicontrol with any tuning condensers 18, 19 which may be employed in the radio frequency input circuit 2 of the receiver whereby the frequency of the oscillator is maintained different by a constant amount from the frequency to which the radio receiving circuits 20 of the receiver are tuned. In this way a constant intermediate frequency is produced for all received signals.

The first detector 3 of the receiver may of course be of any suitable type but is indicated 25 as one in which the oscillations received from the antenna 1 are supplied to a grid 20 near the cathode of the discharge device employed whereas oscillations from the local oscillator are supplied to a grid 21 more removed from the 30 cathode and which is shielded by shield grids 22 and 23 both from the anode and from the control grid 20, these shield grids being supplied with suitable positive operating potential from a source 24 and connected to the cathode through 35 a bypass condenser 25.

The signal seeking circuit employed in the receiver illustrated comprises an electron discharge device 26 having its anode and cathode effectively in shunt with the oscillating circuit 40 11 of the electron discharge oscillation generator 8. It will be noted that its cathode is connected through bias resistor 27 and bypass condenser 28 to ground and hence to one side of the oscillating circuit 11. Its anode is also connected 45 through resistance 30 to the opposite side of the oscillating circuit. The control grid of the discharge device 26 is connected to the same side of the oscillating circuit as the anode through blocking condenser 29 and resistance 31, this 50 control grid being also connected through a conductor 32 to the output of the rectifier 6.

This rectifier 6 and the frequency discriminating circuit 5 associated therewith are arranged to supply to the conductor 32 a potential which 55

varies from a predetermined value, as for example ground potential, either positively or negatively, depending upon the variations of the intermediate frequency from a desired fixed value. In this way the impedance between the anode and cathode of the discharge device 26 is varied, this impedance for reasons presently to be explained effecting a desired change in the frequency produced by the oscillator 8. Thus for example if the intermediate frequency increases or decreases for any cause, such for example as movement of the tuning control within certain predetermined limits, the impedance of discharge device 26 is varied in such a way as to produce a change in frequency of the oscillation generator which tends to restore the intermediate frequency to its normal value.

To effect this control the frequency discriminating circuit 5 is employed, this circuit comprising a transformer having a primary winding 41 and a secondary winding 33, both of these windings being tuned to the desired fixed intermediate frequency. The primary winding is connected between ground and the midpoint of the secondary winding 33 through a condenser 34. The opposite terminals of the secondary winding 33 are connected to the respective anodes of diodes 35 and 36, the cathodes of these diodes being connected together for alternating currents through condenser 37 and for direct currents through resistances 38 and 39. The cathode of diode 36 is grounded and the midpoint between resistances 38 and 39 is connected to the midpoint on secondary winding 33 through a choke coil 40.

As thus described the operation of the system is as follows:

If we assume that the tuning control of the radio receiver is adjusted for accurate resonance with the received carrier wave, then the intermediate frequency has the desired value to which the primary and secondary windings 41 and 33 are each tuned. The voltage across the secondary winding of the transformer, in accordance with well known theory, is displaced in phase from the voltage across the primary by 90°. With the connections shown the voltage of the primary is connected in series with one half of the voltage on the secondary through discharge device 35 and condenser 37 and it is connected in series with the other half of the voltage on the secondary through discharge device 36. Because of the quadrature relation between the primary and secondary voltages the voltage on one half of the secondary leads the voltage on the primary by 90° whereas that on the other half of the secondary lags behind the voltage on the primary by 90°. Thus the voltage applied to the two diodes 35 and 36 when the intermediate frequency is at its desired value is equal and accordingly equal values of unidirectional currents flow through each of the diodes and hence through resistances 38 and 39. It will be observed that these resistances are poled oppositely, that is, the voltages across the two are opposite in polarity in the circuit between conductor 32 and ground with the result that the conductor 32 is at ground potential when the intermediate frequency is at the desired value.

The quadrature relation between the primary and secondary voltages of the transformer 5 exist, however, only when the oscillations supplied thereto have the desired intermediate frequency. If this frequency changes in either direction the phase of the secondary voltage varies from its 90°

relation with the primary voltage in one direction or the other dependent upon whether the frequency increases or decreases. For example, if the frequency increases, the phase shift may be in such a direction that the voltage on the upper half of the secondary winding approaches the aiding relation with the primary voltage whereas that on the lower half of the secondary winding approaches the opposing relation with the primary voltage. Thus the voltage applied to diode 35 increases and that applied to diode 36 decreases with the result that the unidirectional potential on resistance 38 increases whereas that on resistance 39 decreases and the conductor 32 thus becomes positive with respect to ground. On the other hand, if the intermediate frequency decreases, an opposite shift in phase of the secondary voltage occurs with the result that the larger alternating current voltage is supplied to diode 36 and the potential on resistance 39 increases whereas that on resistance 38 decreases and the conductor 32 is driven negative with respect to ground.

Discharge device 26 responds to these variations in potential of the conductor 32 to produce corresponding variations in frequency of oscillations generated by the device 8. The anode and cathode of this discharge device may be caused to act effectively either as an inductance or as a capacitance in shunt with the oscillatory circuit 11. With the circuit arrangement shown it acts effectively as an inductance. It will be observed that the oscillations of the circuit 11 are applied through resistances 30 and 31 and blocking condenser 29 to the control grid 42 of the discharge device 26 and through resistance 39 to the anode. The voltage on the grid 42, since the impedance between the grid 42 and the cathode is essentially capacitive, lags behind the voltage of the oscillating circuit by 90° and since the current in the anode is in phase with the grid voltage it also lags behind the voltage of the oscillating circuit by substantially 90°. In other words the anode to cathode impedance of the discharge device is effectively inductive. The value of this effective inductance may be varied by varying the unidirectional potential applied to the control grid 42 thereby varying the intensity of the current flowing in the anode circuit. Thus when the control grid becomes positive the effective inductance is reduced and when it becomes negative the effective inductance is increased. This effective inductance may be caused to vary the natural period of the oscillator circuit 11 to effect the desired frequency changes.

Certain difficulties, however, may be encountered in the use of such a system owing to the fact that there is a certain predetermined impedance arising from a capacitance between the anode and cathode of the discharge device 26 which is effectively in shunt with the oscillating circuit 11. This capacity is sufficient to throw the oscillating circuit 11 out of alignment with the tuned circuits of the amplifier 2. That is, for example, let us suppose that the conductor 32 were permanently grounded. The anode capacitance of the discharge device 26 is such that if the tuning control be varied throughout the range to which the receiver is adapted to respond, the intermediate frequency may vary from one end of the range to the other notwithstanding that the components of the circuit 11 are chosen for a constant intermediate frequency at all positions of the tuning control with the discharge device 26 removed from the circuit. To avoid

5 this misalignment produced by the discharge device 26 and in accordance with my invention the
 10 resistance 30 is included in the circuit. This resistance may be chosen of such a value that
 15 the capacitance between the anode and cathode
 20 of the discharge device or other capacitance in
 25 the circuit of the discharge device is prevented
 30 from affecting the frequency of the oscillating circuit 11. At the same time this resistance may
 35 be small enough so that it does not materially re-
 40 duce the control of the frequency produced by
 45 the discharge device 26 in response to variations
 50 in potential on conductor 32. This will be under-
 55 stood, for example, if the discharge device 26
 60 be considered as a capacitance connected across
 65 the oscillating circuit through resistance 30. If
 70 the resistance 30 were zero the capacitance would
 75 be connected directly in the oscillating circuit,
 80 whereas if the resistance were infinite the capac-
 85 itance would be disconnected from the oscillating
 90 circuit. It has been found, however, that by the
 95 use of an intermediate value of resistance 30 the
 100 effect of this capacity can be reduced to an ex-
 105 tent such that it is unobjectionable in the opera-
 110 tion of the receiver. I employ a resistance of
 115 about five thousand ohms for this purpose. This
 120 value of resistance is very small as compared with
 125 the resistance between the anode and cathode of
 130 the discharge device 26, and accordingly varia-
 135 tions in the latter resistance produced by varia-
 140 tions in the grid potential are so large relative
 145 to the value of resistance 30 that the latter ele-
 150 ment does not greatly reduce the control effected
 155 by the discharge device 26.

35 In its practical application the resistance 30
 40 may be connected in close proximity to the oscil-
 45 lating circuit 11 thereby to minimize capacitance
 50 produced by the conductor adjoining it with the
 55 oscillating circuit.

40 While I have shown a particular embodiment
 45 of my invention, it will of course be understood
 50 that I do not wish to be limited thereto since this
 55 embodiment is presented by way of illustrating
 60 the principles involved. Many modifications may
 65 be made both in the arrangement shown and in
 70 the instrumentalities employed and I contem-
 75 plate by the appended claims to cover any such
 80 modifications as fall within the true spirit and
 85 scope of my invention.

50 What I claim as new and desire to secure by
 Letters Patent of the United States is:

1. The combination, in a radio receiver having
 55 an adjustable element adapted to tube an input
 60 circuit of said receiver over a range of frequencies,
 65 an electron discharge oscillation generator hav-
 70 ing an adjustable element adapted to tune said
 75 oscillator over a corresponding range of fre-
 80 quencies, means to produce a beat frequency be-
 85 tween received oscillations and oscillations pro-
 90 duced by said oscillation generator, means in-
 95 cluding a mechanical connection of said adjust-
 100 able elements for maintaining said oscillator fre-
 105 quency different by a predetermined constant
 110 amount from the frequency to which said input
 115 circuit is tuned, means responsive to variations
 120 in said beat frequency to control the frequency of
 125 said oscillation generator, said last named means
 130 comprising an electron discharge device having
 135 electrodes connected to said oscillation generator,
 140 said electrodes having a predetermined impedance
 145 therebetween which cause an undesired varia-
 150 tion of the difference between the frequency of
 155 said oscillator and the frequency to which said
 160 input circuit is tuned as said receiver is tuned
 165 over said range of frequency, and means for

greatly reducing the effect of said predetermined
 5 impedance on the alignment between said oscil-
 10 lator and said input circuit tuning while permit-
 15 ting said last named means effectively to control
 20 the frequency of said oscillation generator. 5

2. The combination, in a radio receiver adapted
 10 to receive oscillations varying over a range of
 15 frequencies, a source of oscillations having a fre-
 20 quency determining oscillatory circuit, means to
 25 produce a beat frequency between said received
 30 oscillations and oscillations produced by said
 35 source, means to vary the frequency of said
 40 source to maintain said beat frequency at a de-
 45 sired constant value for reception of any fre-
 50 quency in said range, means responsive to varia-
 55 tions in said beat frequency from a normal fre-
 60 quency to control the frequency of said source,
 65 said means comprising an electron discharge de-
 70 vice having an anode and cathode with a normal
 75 impedance therebetween connected across said
 80 oscillatory circuit through a resistance, and
 85 means to vary the impedance between said anode
 90 and cathode from said normal value to vary said
 95 frequency, said resistance having a value large in
 100 comparison to the inherent anode to cathode im-
 105 pedance and small in comparison to the con-
 110 trolled anode to cathode impedance. 15

3. In combination, a reactance, an electron dis-
 115 charge device having electrodes connected at
 120 different points on said reactance and having a
 125 predetermined impedance between said elec-
 130 trodes, a resistance connected in circuit between
 135 one of said electrodes and said reactance and hav-
 140 ing a value large in comparison to said predeter-
 145 mined impedance between said electrodes and
 150 small in comparison to the controllable im-
 155 pedance between said electrodes whereby said pre-
 160 determined impedance between said electrodes
 165 has substantially no effect upon the reactance
 170 between said points, and means to vary the ef-
 175 fective reactance between said points by control-
 180 ling the impedance between said electrodes. 20

4. In combination, two circuit points between
 185 which alternating electromotive force exists,
 190 means to vary the effective reactance between 45
 195 said points, said means comprising an electron
 200 discharge device having a pair of electrodes con-
 205 nected respectively to said points, said electrodes
 210 having capacitance therebetween, a resistance
 215 connected in circuit between one of said points 50
 220 and the respective electrode, said resistance being
 225 sufficiently high substantially to reduce the effect
 230 of said capacitance upon the effective reactance
 235 between said points yet sufficiently low as to have
 240 negligible effect upon the simulated reactance 55
 245 between said two circuit points by said electron
 250 discharge device, means to phase the current
 255 flowing between said electrodes relative to said
 260 electromotive force to simulate a reactance con-
 265 nected between said points, and means to vary 60
 270 the magnitude of said current.

5. The combination, in a superheterodyne type
 275 of radio receiver having aligned input and oscil-
 280 lator circuits tunable over a range of frequencies,
 285 of means for producing from locally generated 65
 290 oscillations and received signal oscillations beat
 295 frequency oscillations having a desired constant
 300 value as said receiver is tuned over said range of
 305 frequencies, means responsive to variations in the
 310 frequency of said beat frequency oscillations 70
 315 from said desired constant value for controlling
 320 the frequency of said locally generated oscilla-
 325 tions, said last named means including an elec-
 330 tron discharge device having electrodes with a
 335 predetermined impedance therebetween con- 75

- 5 nected to points on said oscillator circuit, said predetermined impedance causing an undesirable variation of alignment between the tuning of said oscillator and said input circuit as said receiver
10 is tuned over said range of frequencies, and means including an impedance connected in series relation with said discharge device electrodes across said points on said oscillator circuit for greatly reducing the effect of said predetermined impedance on the alignment between said oscillator and said input circuit while permitting said last named means effectively to control the frequency of said oscillation generator.
- 15 6. The combination, in a superheterodyne type of radio receiver having aligned input and oscillator circuits tunable over a range of frequencies, of means for producing from locally generated oscillations and received signal oscillations beat frequency oscillations having a desired constant value as said receiver is tuned over said range of frequencies, means responsive to variations in the

frequency of said beat frequency oscillations from said desired constant value for controlling the frequency of said locally generated oscillations, said last named means including an electron discharge device having electrodes with a predetermined impedance therebetween connected to points on said oscillator circuit, said predetermined impedance causing an undesirable variation of alignment between the tuning of said oscillator and said input circuit as said receiver is tuned over said range of frequencies, and means including a resistance connected in series relation with said discharge device electrodes across said points on said oscillator circuit and having a proportioned value of resistance greatly to reduce the effect of said predetermined impedance on the alignment between said oscillator and said input circuit while permitting said last named means effectively to control the frequency of said oscillation generator.

10 15 20 ROBERT B. DOME.

CERTIFICATE OF CORRECTION.

Patent No. 2,166,805.

July 18, 1939.

ROBERT B. DOME.

It is hereby certified that error appears in the printed specification of the above numbered patent requiring correction as follows: Page 3, first column, line 53, claim 1, for the word "tube" read tune; and that the said Letters Patent should be read with this correction therein that the same may conform to the record of the case in the Patent Office.

Signed and sealed this 29th day of August, A. D. 1939.

(Seal)

Leslie Frazer,
Acting Commissioner of Patents.
